UNITED STATES PATENT OFFICE.

PAUL W. KNAUF, OF CYNWYD, PENNSYLVANIA, ASSIGNOR TO SCHUTTE AND KOERTING COMPANY, OF PHILADELPHIA, PENNSYLVANIA, A CORPORATION OF PENNSYLVANIA.

FAN BLOWER.

Application filed June 2, 1922. Serial No. 565,345.

To all whom it may concern:

Be it known that I, PAUL W. KNAUF, a citizen of the United States, and a resident of Cynwyd, in the county of Montgomery and State of Pennsylvania, have invented an Improvement in Fan Blowers, of which the following is a specification.

My invention relates to fan structures in which the fan is situated within a casing, and it has for its general object to provide novel means for enabling the removal of the fan from such casing for repair or other purpose.

A further object is to provide novel means for supporting said fan so that it may be readily inserted into or removed from the said casing without disconnecting therefrom either the incoming or outgoing pipes or conduits through which air, gases and the like are or may be conveyed.

A still further object of the invention is to provide a novel construction and arrangement wherein and whereby one of the sides of the casing, when disconnected from the main or body portion of the casing, is adapted to be supported upon the fan structure.

Another object of the invention is to provide novel means for adjustably connecting the casing of the fan to its supporting cradle.

Other objects and advantages of the invention will be pointed out in the detailed description thereof which follows or will be apparent from such description.

In order that the invention may be readily understood and its practical advantages fully appreciated, reference may be had to the accompanying drawings in which is depicted one form of embodiment thereof.

However, it will be understood that changes in the details of construction may be made within the scope of the claims without departing from the invention.

In the drawings:

Fig. 1 is a view in side and sectional elevation of a construction of fan-blower embodying my invention;

Fig. 2 is a view in end elevation looking toward the right in Fig. 1;

Fig. 3 is a view in side elevation of a portion of the casing of the fan and its support;

Fig. 4 is a view similar to that shown in Fig. 1 but with the fan and its support in

different position from that in which it is shown in said Fig. 1;

Fig. 5 is a transverse sectional view taken on the line 5—5 of Fig. 4; and

Fig. 6 is a fragmentary sectional view of a portion of the casing and its support, showing the means employed for adjustably connecting the casing to its support.

Referring to the drawings: 1 designates a base upon which are mounted the cradle supports 2 for the fan casing. The top edges of these supports are concaved, as indicated at 3 in Figs. 2 and 5, and said supports are provided with openings 3^a therethrough as indicated.

The casing comprises the central, generally circular portion 4 having openings in the opposite sides thereof, which openings are surrounded by laterally extending flanges 5 and 6, each of which terminates in outwardly extending annular flange portions 7 and 8; that is to say, flanges which extend substantially at right angles to the axis of the casing. Cover plates 9 and 10 are provided, which plates are provided with flanges 11 and 12 at their outer edges which

correspond with the flanges 5 and 6, and also with outwardly extending annular flange portions 13 and 14 which correspond with the flanges 7 and 8 and are adapted to be secured thereto by means of threaded bolts 15 and 16 provided with nuts, as shown. The flanges 7 and 13 and 8 and 14 are adapted to be seated upon the upper edges of the supports 2 and are adapted to be held in adjusted position thereon by means of clevis-like binding and holding members 17. The inner spaced and unconnected ends of the opposite sides of these members are provided with openings through which certain selected ones of the bolts 15 and 16 are extended, as indicated in the drawings. The inner ends of clamping or binding screws 18, which have screw-threaded connection with the integral connections between the outer ends of the opposite sides of the said members, are adapted to contact with the outer edges of portions of the supports 2, as best shown in Fig. 6 of the drawings, for drawing and holding the edges of the flanges 7 and 13 and 8 and 14 downwardly against the seats provided therefor in the upper edges of the said supports. By loosening these binding screws the fan casing may be

- adjusted rotatably to such position as may be desired and thereafter secured by tightening said screws. The cover 10 is provided with a central hollow flange-like projection 20 to which one end of an inlet pipe or conduit 21 may be secured. An outlet pipe or conduit 23 is secured to the end of a tangentially arranged hollow projection 24 leading from the fan casing.
- 10 The fan comprises blades 30 of the usual known construction which project radially from a hub 31 which is mounted upon and secured to a sleeve 32 which in turn is secured upon the inner end of a shaft 33 driven from a motor 34 and the shaft 35 to which it is connected by means of a coupling 36. The fan is held upon the shaft by means of a nut and washer 37 and 38. The shaft 33 is supported upon roller bearing devices 40 at the opposite ends of a supporting cylindrical casing or housing 41 upon the upper end of a bracket support 45 which is slidably connected with and supported upon the base 1. The said support 45 is adapted to be held in adjusted position by means of the binding screws 45^a. The bracket support 45 is provided with a laterally projecting extension 46 to which the motor 34 is secured and upon which it is supported.
- 15 The cover or closure portion 9 of the casing is provided with a flanged opening 48 at its center into which an annular flange-like projection 49 from the hub portion 31 of the fan projects. The said projection fits closely within the said opening and by means of suitable packing is rendered air-tight.
- 20 For the purpose of rigidly connecting the closure 9 of the casing with a part of the bracket support 45 in order to retain it in proper relation to the fan, I have provided a bracket, comprising oppositely and upwardly extending arms 50 and 51, which is secured by means of screw bolts 52 to the upper side of the cylindrical casing or housing 41. The outer ends of these arms are secured by means of screws 53 to the said closure 9. For the purpose of aiding in the retention of the closure in proper position and relation to other parts of the structure and to prevent it from tilting, I have provided abutment blocks 54 which are secured to the supporting frame 45 upon opposite sides of a central vertical plane through the apparatus which blocks are adapted to contact with the side of the said closure near the lower edge thereof.
- 25 By removing the bolts 15, thus disconnecting the closure 9 from the portion 4 of the casing and releasing or loosening the binding screws 45^a, it will be seen that the bracket support 45 together with the motor and other parts carried thereby including the fan supported upon the inner end of the shaft 33 may be adjusted toward and from the casing to insert and remove the fan into and from the casing. As the parts are adjusted in Fig. 4 the fan is within the casing while as they are adjusted in Fig. 1 the fan is without the casing. The latter position affords access to the fan and the structure associated therewith so that the same may be inspected or readily repaired if repair be necessary.
- 30 By reason of the employment of my invention it will be seen that the support for the fan together with the fan may be moved into position to remove the fan from the casing without disturbing or interfering with the connections between the inlet and outlet pipes or conduits with the casing; and also it will be seen that the motor and connections between the same and the fan are carried upon the same support as the fan and are moved therewith.
- 35 Having thus described my invention, what I claim and desire to secure by Letters Patent is:
1. In a fan-blower, the combination of a casing, a fan, a bracket support for the said fan, the said support and fan being adapted to be adjusted so as to position the said fan within the said casing or outside of the same, and a closure for the opening within the casing through which the said fan is adapted to be inserted and removed, the said closure being supported upon a portion of the fan-supporting structure. 90
2. In a fan-blower, the combination of a fan, a casing for the fan having an opening in one side thereof through which the said fan is adapted to be inserted and withdrawn, an adjustable bracket support for supporting the said fan, which support is adapted to be adjusted toward and from said casing in order to insert and remove the said fan into and from said casing, and a closure for the said opening, which closure is supported upon a portion of the fan-supporting structure and is adapted to be adjusted with the said fan and the said bracket support. 100
3. In a fan-blower, the combination of a fan, a casing for the said fan, said casing being provided with an opening in one side thereof through which the said fan is adapted to be inserted and removed from said casing, an adjustable support for the said fan, which support is adapted to be adjusted toward and from said casing to effect insertion and removal of said fan into and out of said casing, a closure for said opening, and means carried upon the said support and having connection with the said closure for supporting the same. 115
4. In a fan-blower, the combination of a rotary fan having a hub provided with an outwardly extending annular projection, a casing for the said fan, said casing having 120
5. In a fan-blower, the combination of a fan, a casing for the said fan, said casing being provided with an opening in one side thereof through which the said fan is adapted to be inserted and removed from said casing, an adjustable support for the said fan, which support is adapted to be adjusted toward and from said casing to effect insertion and removal of said fan into and out of said casing, a closure for said opening, and means carried upon the said support and having connection with the said closure for supporting the same. 125
6. In a fan-blower, the combination of a rotary fan having a hub provided with an outwardly extending annular projection, a casing for the said fan, said casing having 130

a flanged opening in one side thereof through which the said fan is adapted to be inserted and removed, an adjustable support for the said fan, which support is adapted to be 5 adjusted toward and from the said casing to effect the insertion and removal of said fan into and from said casing, a closure for the said opening, which closure is provided with a central opening with which the said 10 annular projection is in engagement and also with an annular flange which is adapted to be secured to the flange of the said casing, means carried by the said support and having connection with the said closure for 15 holding the same in relatively fixed position, substantially as described.

5. In a fan-blower, the combination of a rotary fan having an annular projection extending outwardly from and concentri- 20 cally of the hub thereof, a casing having a flanged opening in one side thereof, a shaft upon and to which the said fan is secured, a motor for driving said shaft, an adjustable support for supporting said shaft and motor, 25 a closure for closing the said opening, said closure being provided with a central opening into which the said projection extends, and also with a peripheral flange which is

adapted to be secured to the flange upon said casing, a bracket member secured to 30 said support and having connection with portions of the closure at points upon one side of the said shaft, and means carried by the said support for contacting with portions of the said closure upon the opposite 35 side of said shaft to prevent tilting of said closure when disconnected from the said casing.

6. In a fan-blower, the combination of a casing having an opening in one side 40 thereof, a support therefor, means whereby said casing may be adjusted to and held in different positions upon its support, a rotary fan, an adjustable means for supporting said fan, which means is adapted to be moved 45 toward and from the said casing to move the said fan toward and from said casing to effect insertion thereof through said opening into and from the said casing, and a closure carried by said support and mov- 50 able therewith for closing and opening the said opening.

In testimony that I claim the foregoing as my invention, I have hereunto signed my name this 26th day of May, A. D., 1922.

PAUL W. KNAUF.
